DESCRIPTION

U.S. PATENT DOCUMENTS

FIG. 1 is a perspective view as seen from the top, front, and left side of a flexible jacket for a slow cooker showing our new design;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a bottom plan view thereof; and,

FIG. 8 is a perspective view as seen from the top, front, and left side of a flexible jacket for a slow cooker similar to FIG. 1 but showing the flexible jacket in an open position.

The drawings are shaded to represent a flexible material which is not necessarily woven.

The broken lines in FIGS. 1 and 8 showing the slow cooker handles and the slow cooker lid within the interior of the flexible jacket are used for illustrative purposes only and form no part of the claimed design.
